[57] CLAIM

The ornamental design for an ablution unit, as shown and described.

DESCRIPTION

FIG. 1 is a perspective front view of an ablution unit showing my new design;

FIG. 2 is a side elevational view thereof, taken from the opposite side;

FIG. 3 is a front elevational view thereof, FIGS. 1 to 3 showing the unit in condition for use;

FIG. 4 is a side elevational view corresponding to FIG. 2; and

FIG. 5 is a front elevational view corresponding to FIG. 3, both FIGS. 4 and 5 showing my ablution unit in position for storage.

Fig. 1
